UNITED STATES PATENT OFFICE.

DANIEL MARTIN TAULBEE, OF GRAY, KENTUCKY, ASSIGNOR OF TWO-
THIRDS TO W. A. TAULBEE AND F. E. SAMPSON, OF SAME PLACE.

BICYCLE SHOULDER-BRACE.

SPECIFICATION forming part of Letters Patent No. 626,736, dated June 13, 1899.

Application filed September 28, 1898. Serial No. 692,096. (No model.)

To all whom it may concern:

Be it known that I, DANIEL MARTIN TAULBEE, a citizen of the United States, residing at Gray, in the county of Knox and State of Kentucky, have invented certain new and useful Improvements in Bicycle Shoulder-Braces; and I do declare the following to be a full, clear, and exact description of the invention, such as will enable others skilled in the art to which it appertains to make and use the same, reference being had to the accompanying drawings, and to the letters of reference marked thereon, which form a part of this specification.

The special object of the invention is to furnish an elastic support and brace to the shoulders of a bicycler as he rides. This renders his stooping position less irksome and enables him to ride much farther at a considerable velocity.

Figure 1 of the drawings is a side elevation showing my invention applied, and Fig. 2 a front elevation thereof.

In the drawings, A represents a flat S-shaped spring with a horizontal bottom, concaved on the under side to fit snugly over the top bar of a bicycle, and a vertical upper end perpendicularly slotted.

C C are clamps, of any suitable construction, which serve to hold the spring A to the top bar B of the bicycle, while D D are two arms secured by a screw and nut to the vertical projection of the spring. The arms have horizontal slots f, which cross the vertical slot a in the spring, while a set-screw d passes through both slots and is clamped by a nut on the inner side. I may use two set-screws d' d' at the ends of the horizontal slots with end nuts to more fully secure the arms in position, but I do not deem them absolutely necessary. This allows them to be set higher or lower and at a greater or less distance apart. The shoulder-hooks may be provided with pneumatic or other pads, so that they will furnish a soft bearing as well as an elastic support.

The hooks F and arms D have horizontal

meeting ends to form a rest for the shoulders of the rider when he stoops over to throw his weight to the front, while the hooks over the shoulders form a brace when he raises himself up to an approximately erect position.

The attachment will be made in different sizes, so as to be adapted to frames and riders of varying size.

It will be noticed that the upper curve of the S-spring A projects over the handle-bar, but in the vertical plane of the frame, so that the weight of the rider will be evenly balanced on each side.

My improvement is for riders on the road, not for scorchers or racers. The purpose is to enable a rider to sit upright or from that to an angle of forty-five degrees to the top rod B, while his shoulders are supported in the rests F. This is effected by the form of my spring and the way in which it connects with the top rod and shoulder-arms, being readily adjustable on the top rod B to suit the wishes of each rider.

I find in practice that this attachment greatly lessens the fatigue of the rider, augments his power of endurance, and very much increases the pleasure of riding.

I am aware that a rest has been used on one bicycle attachment and a brace upon another, but I construct my attachment so as to give both a spring-rest and a spring-brace. Hence

What I claim as new is—

A bicycle attachment having shoulder-hooks F and arms D, with horizontal meeting ends as shown, in combination with the S-spring A adapted to be clamped on the top rod of a bicycle at its lower end and at its upper end to be bolted to said arms, whereby said attachment may form both a brace and a rest for the rider as described.

In testimony whereof I affix my signature in presence of two witnesses.

DANIEL MARTIN TAULBEE.
